UNITED STATES PATENT OFFICE.

ALBERT HORN, OF ST. LOUIS, MISSOURI.

APPARATUS FOR REPAIRING AND TESTING RADIATORS.

1,419,260.

Specification of Letters Patent. Patented June 13, 1922.

Application filed May 16, 1921. Serial No. 470,217.

To all whom it may concern:

Be it known that I, ALBERT HORN, a citizen of the United States, residing at the city of St. Louis, in the State of Missouri, have 5 invented certain new and useful Improvements in Apparatus for Repairing and Testing Radiators, of which the following is a specification.

My invention has relation to improvements in testing machines for radiators, particularly automobile radiators, and consists 10 in the novel details of construction more fully set forth in the specification and pointed out in the claims.

15 The object of the present invention is to provide a device that will readily immerse the radiator in a suitable liquid without manual handling of the radiator. A further object is to provide a testing machine 20 of the character referred to that may be operated by one person; one that is simple; and one possessing further and other advantages better apparent from the following description in connection with the accompanying drawings in which—

Figure 1 is a top plan of my improved testing machine; Fig. 2 is a side elevation thereof; Fig. 3 is a side elevation of one supporting arm, with the hanger and part of 30 the platform supported thereby; Fig. 4 is a cross-section through one side of the table showing an edge view of the platform supporting arm and the pinion for oscillating the same; Fig. 5 is an enlarged view of the 35 notched sector and pawl for holding the platform in place; Fig. 6 is a side view of the adjustable bearing block.

Referring to the drawings, 1 represents an angle iron frame provided at one end 40 with a drain and working table 2. The frame is supported on the legs 3, and has a tank 4 positioned within the angles and suitably secured thereto. Adjustable bearing blocks 5 are secured to base plates 6, by 45 means of bolts 7, said bolts traversing slots 8 in the blocks 5 and being screw-seated in the base plates 6, the latter being suitably secured to the frame 1. The engaging surfaces of blocks and plates are provided with 50 teeth 9 to prevent accidental displacement of the blocks 5 after the same have been adjusted. Shafts 10 are mounted in the blocks 5, and have sprockets 11 fixed on their outer ends and toothed disks 12 keyed near their 55 inner ends within the tank 4. The shafts 10 terminate at their inner ends in studs 13

on which are mounted supporting arms 14. The arms 14 terminate in toothed disks 15 which engage the disks 12 and are held in engagement therewith by nuts 16 passed over 60 the studs 13. Hanger arms 17 are supported on pins 18 projecting from supporting arms 14, the upper ends of arms 17 terminating in hooks 19 which are hooked over the pins, and bars 20 are secured to the lower ends of 65 the arms 17, said bars supporting a perforated platform 21.

A shaft 22 is mounted in brackets 23 fixed to the frame 1 below the tank 4, said shaft extending entirely across the frame, 70 and sprockets 24 are keyed on the ends of the shaft 22, one of said sprockets having a series of operating handles 25 fixed to it. A sector 26 is keyed on one end of the shaft 22, said sector having a plurality of notches 75 27 on its periphery, and a dog 28 is mounted on the frame 1 adjacent the sector 26 so that when desired said dog may be dropped into any one of the notches 27 in order to lock the operating mechanism against movement.

On each side of the frame 1 are mounted shafts 29 and a large sprocket 30 and small sprocket 31 are mounted on each shaft 29, the large sprocket 30 being driven by a chain 85 32 from sprocket 24. The motion thus transmitted to sprocket 31 is carried to sprockets 11 by a chain 33, causing shafts 10 to be rotated, oscillating supporting arms 14 downwardly and lowering the platform 21.

The operation of my invention may briefly be described as follows:

A radiator 50 that is to be tested for leaks is placed on the platform 21, the radiator, of 95 course, being connected to a suitable air supply (my invention having nothing to do with air or water connections) and the operator releases the dog 28 whereupon he may rotate the shaft 22 by the handles 25. The 100 motion of shaft 22 is transmitted to sprockets 11 through the chain 32, sprockets 30, 31, and chain 33, whereupon the arms 14 are rocked downwardly lowering the hangers 105 17 and platform 21 into the water. If desired the platform may be held in any position by locking the sector 26 with the dog 28. Should it be desired to decrease the distance that the platform descends into the tank 4, the nut 16 is unscrewed whereupon 110 the arm 14 is given angular adjustment by rotating disk 15 the required amount, when

the nut is again tightened. During the testing operation, if the operator desires to support the radiator 50 in an upright position in order to inspect same, he may place same 5 edgewise on an opening 51 provided in the platform 21.

When it is desired to take up the slack in the chain 33, the blocks 5 may be released from plates 6 by unscrewing studs 7, after 10 which they are adjusted outwardly the amount required and the studs 7 again tightened. A slotted opening 34 in the tank wall permits the shaft 10 to be moved with the block 5.

15 The advantage of providing the hangers 17 with hooks 19 lies in their ready detachability so that the platform can be removed from the tank in order to clean the latter.

Obviously the invention is susceptible to 20 modifications without departing from the spirit of the same.

Having described my invention I claim:

1. In a machine of the character described, 25 a suitable frame, a tank supported thereby, a plurality of supporting arms rotatably mounted on said frame, hangers detachably suspended from the arms, a platform within the tank and secured to said hangers, and means for oscillating the supporting arms 30 to raise and lower the platform.

2. In a machine of the character described, 35 a suitable frame, a tank supported thereby, a plurality of supporting arms rotatably

mounted on said frame, hangers detachably suspended from the arms, a platform within 35 the tank and secured to said hangers, means for oscillating the supporting arms to raise and lower the platform, and means for angularly adjusting the supporting arms to regulate the distance said platform moves. 40

3. In a machine of the character described, 45 a suitable frame, a tank supported thereby, a plurality of supporting arms rotatably mounted on said frame, hangers detachably suspended from the arms, a platform within the tank and secured to said hangers, means for oscillating the supporting arms, to raise and lower the platform, and means for locking the platform in any predetermined position. 50

4. In a machine of the character described, 55 a suitable frame, a tank supported by said frame, a plurality of shafts mounted on the frame near the top thereof, said shafts having supporting arms on their inner ends, a platform detachably supported by said arms, an actuating shaft, a pair of counter shafts, means for driving the counter shafts from the actuating shaft, means for driving the first mentioned shafts from the counter shafts, 60 whereby the platform may be raised and lowered, and locking means for maintaining the platform in any predetermined position.

In testimony whereof I hereunto affix my signature.

ALBERT HORN.
